US00D379418S

United States Patent [19]
Skinner

[11] **Patent Number:** **Des. 379,418**
[45] **Date of Patent:** ****May 27, 1997**

[54] **CUTTING LINE FOR A ROTATING LINE TRIMMER**

[75] Inventor: **David B. Skinner**, Columbia, S.C.

[73] Assignee: **Shakespeare Company**, Columbia, S.C.

[**] Term: **14 Years**

[21] Appl. No.: **39,264**

[22] Filed: **May 25, 1995**

Related U.S. Application Data

[60] Division of Ser. No. 29,442, Oct. 6, 1994, Pat. No. Des. 365,734, which is a continuation-in-part of Ser. No. 834,520, Feb. 12, 1992, Pat. No. Des. 364,079.
